METHOD OF MAKING SCISSORS

William A. Zeidler, Bronxville, N. Y., assignor to
Change-A-Blade Corporation, New York, N. Y.,
a corporation of New York

Application May 10, 1939, Serial No. 272,814

3 Claims. (Cl. 76—104)

The object of my invention is to provide a method of making scissors with removable cutting blades which will always fit accurately in the blade-retaining scissor elements and not be

5 warped or distorted during the hardening process to which the blades are subjected in their manufacture, which hardening process forms a part of the present invention. This object is accomplished by my invention, one embodiment of 10 which is hereinafter more particularly set forth.

When scissors or scissor blades are manufactured according to present-day methods, the blades are stamped from perfectly flat stock and then ground to give them the proper hollow shape required of scissor blades in order to enable them to properly function. This grinding or shaping of the blades usually causes blade distortion, particularly when the blades are stamped from relatively thin sheet metal with the result that the 20 scissors cut poorly and improperly. It has also been found extremely difficult to properly grind scissor blades near their points, with the result that in most scissors of the removable blade type, the cutting near the points of the scissors is extremely poor and inefficient. It has also been found difficult, if not impossible, to secure uniformity in the blades. My invention therefore contemplates a method whereby the blades are stamped from relatively thin sheet metal and the proper shaping and curvature for the entire 30 blade length is imparted to the blades by the method of stamping them, rather than by shaping and grinding processes so that the finished blade is provided with the necessary curvature and also a slight transverse twist enabling it to function with extreme effectiveness.

For a more detailed description of my invention, reference is to be had to the accompanying drawing, forming a part hereof, in which Fig. 1 is a plan view of a pair of scissors embodying my invention; Fig. 2 is an enlarged edge view of the same; Fig. 3 shows a portion of a scissor element with a blade fitted thereon; Fig. 4 is a side elevation of a blade when removed from the holder; Figs. 5, 6, 7 and 8 are sectional views, taken on the corresponding lines of Fig. 3; Fig. 9 shows a portion of a cylindrical surface from which blades are cut and removed, this cylindrical surface showing the way these blades are 40 cut from curved or arched stock; Fig. 10 is an end view of the material of Fig. 9; and Fig. 11 shows a novel pivot for the scissors.

My improved scissors is composed of scissor handle members 2 and 3, a pivot 4 and blades 5, one blade being adapted for detachable secure-

ment to each scissor member. The blades are all made of sheet material and are identical and interchangeable.

Each scissor handle member has a conventional finger hole 6, by means of which these members may be operated about the pivot 4 in the conventional manner. Close to the pivot 4 each handle member 2 and 3 has a portion removed equal to the thickness of the blade 5 and this extends clear to the ends remote from the parts 6. 10

As is well known, in ordinary scissors it is necessary to give the cutting edges a peculiar shape and adjacent to them the scissors have warped or twisted surfaces. The shape and surfaces are preserved in the members 2 and 3, but these 15 members do not touch beyond the pivot, being separated at all times by at least two thicknesses of each blade 5, or the thickness of two blades 5. The means for holding these blades 5 will now be described. 20

Each of these blades has a hole 7 which surrounds the pivot 4 and beyond this each blade has a lateral lug 8 struck therefrom (see Fig. 8) so as to enter and fit a corresponding hole 9 in a scissor member. Near the point, as shown in 25 Fig. 7, an inclined lug 10 takes under a tongue 11 formed in the scissor member. These three, that is the pivot 4, the lug 8 and the lug 10, hold the blade true. Each blade is inserted or removed by removing the pivot 4, separating the scissor elements and removing the old blade, if one be in place, by sliding the same towards the point 2 that the parts 10 and 11 disengage. When a new blade is inserted the reverse occurs and the parts 10 and 11 are brought into engagement and thereafter the lug 8 is sprung into the socket or opening 9 and the same is done for both scissor members and thereafter the members are put together and the pivot 4 inserted. This pivot is generally a screw of the conventional type, but 40 may be of the kind shown in Fig. 11. 30

In Fig. 11, the pivot 4 is a split screw with a central bore therein, in which is placed the sliding wedge 13, which may be driven up or down, as desired. It is driven downwardly in Fig. 11 45 and then the screw 4 is adjusted until the desired tension is on the blades, and thereafter the wedge 13 is driven upwardly so as to bind.

Heretofore many efforts have been made to make blades which could be shaped when the 50 steel is soft and annealed and then after hardening retain its shape. The shape is very important because the fit must be perfect at all times between scissor member and blade. When blades of the prior art have been tempered and 55

ground their shape has been changed so that an imperfect fit has resulted with a correspondingly poor success in the finished article. The problem of making blades which will always fit perfectly has been solved in the following manner.

5 A sheet of metal 12 with a curvature corresponding to that of a cylinder with a diameter of about 14 inches has blades cut from it leaving openings 13 as shown in Fig. 9. From these 10 openings it appears that the axis of each blade runs at something like 25° to an element of the cylinder. This angle may be varied more or less as desired. Since each blade is cut from an arched or curved sheet and at an angle thereto, 15 the resultant blade is not only slightly arched longitudinally, as is apparent from Fig. 2, but the blades also have a very slight transverse twist as is indicated in exaggerated form, in dotted lines in Fig. 4. This twist in the blades causes 20 the two co-operating blades in a scissors to be held in perfect shearing relationship without requiring a too firm blade contact so that the scissors can be operated with a minimum of effort and will cut exceedingly well with but a 25 relatively gentle contact between the two blades. When blades are made as just described, the holes 7 are punched and the parts 8 and 10 struck up, as indicated and one edge 14 is ground and thereafter the blades may be hardened and 30 inserted and used as above described. When the cutting edges become dull the cutting blades are removed and replaced as above specified.

35 Since the blades 5 are stamped from relatively thin sheet metal, it is desirous that the tempering of the same be performed in such a manner as to prevent warpage of the blades. A method in which this can be successfully performed with very satisfactory results is as follows:

40 Each blade is suspended within an open-ended tube of heat-resistant material, with the interior diameter of the tube but slightly larger than the widest part of the blade, and of a length slightly larger than the length of the blade. The hole 7 in each of the blades provides a means 45 by which the blade may be suspended or hung point downward within the tube. While thus disposed within the tube, the blade and tube are located in the annealing furnace and subjected thereby to heat of the required temperature. After being so treated for the required period of time, the blade is next delivered directly from the tube into the cooling oil bath. To avoid 50 contact of the heated blade with atmosphere between the heating and cooling steps, the cooling bath is preferably located adjacent to the

lower open end of the tube from which the heated blade emerges, so that when the blade is released from the means which holds it suspended within the tube, it will be lowered directly into the cooling bath with no intermediate 5 exposure to the air.

By the tempering method just described, the blade is confined in a guide member, such as a tube, during the heating step so that it cannot warp or transversely distort under the action of 10 heat. Since also, the blade is directly and immediately deposited into the cooling bath from the guide tube, no intermediate exposure to atmosphere occurs and warpage cannot occur by reason of the subjection of the heated blade 15 to low temperature before it reaches the cooling bath.

While it is entirely possible that other methods of successfully tempering the blade might be employed, the method herein described has been 20 eminently successful in producing non-warped blades of thin material and of very consistent uniformity in curvature, and when used in conjunction with stamped-out sheet metal blades of the character described, it greatly simplifies the 25 production of and improves the resultant product.

While I have shown and described one embodiment of my invention, it is obvious that it is not restricted thereto, but that it is broad enough 30 to cover all structures that come within the scope of the annexed claims.

What I claim is:

1. The method of making scissor blades consisting in cutting the blades from an arched or 35 curved section of sheet metal at an oblique angle to an axis of the sheet metal section so that the resultant blade is formed with a twist without being ground.

2. The method of making scissor blades consisting in cutting each blade from a sheet of metal concavo-convex in cross section, the blade being cut on a bias with respect to an axis of the sheet, the blade being thereby formed having a curvature by cutting only, forming one of the 45 cutting edges of the blade, aperturing the blade to provide means for holding it to a scissor member, and hardening the blade.

3. The method of making scissor blades consisting in cutting a blade from a piece of concavo-convex sheet metal at an oblique angle to the axis of the sheet to cause the blade so cut to possess without grinding a longitudinal curve and a transverse twist, forming one of the cutting edges of the blade and hardening the blade. 50 55
